UNITED STATES PATENT OFFICE.

LOUIE CLARK HUTCHINSON, OF MONTGOMERY, ALABAMA, ASSIGNOR OF TWENTY ONE-HUNDREDTHS TO BENJAMIN B. CARTER AND THIRTY-FIVE ONE-HUNDREDTHS TO THOMAS C. UNDERWOOD, BOTH OF GARDENA, CALIFORNIA.

ELECTRIC SWITCH LOCK.

Application filed June 14, 1924. Serial No. 720,133.

To all whom it may concern:

Be it known that I, LOUIE C. HUTCHINSON, a citizen of the United States, residing at Montgomery, in the county of Montgomery and State of Alabama, have invented certain new and useful Improvements in Electric Switch Locks; and I do hereby declare the following to be a full, clear, and exact description of the invention, such as 10 will enable others skilled in the art to which it appertains to make and use the same.

The object of this invention is to prevent the theft or the unauthorized use of a motor vehicle by interposing a switch in the 15 circuit of the ignition system and providing said switch with a lock mechanism whereby when the switch is adjusted to break the circuit it may be locked and thereby prevent surreptitious appropriation of 20 the vehicle for any purpose.

Other objects and advantages will be apparent and suggest themselves as the nature of the invention is understood.

While the drawings illustrate an embodiment 25 of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a detail view of a motor vehicle switch lock embodying the invention,

Figure 2 is a top plan view thereof,

Figure 3 is a detail sectional view on the line 3—3 of Figure 2, and

Figure 4 is a sectional detail on the line 4—4 of Figure 3.

Corresponding and like parts are referred to in the following description and designated in the several views of the drawings by like reference characters.

The numeral 1 denotes the floor of a motor 45 vehicle to which is attached a switch lock embodying the invention. The numeral 2 designates the housing which encloses the operating parts, the same being cup-shaped and outwardly flanged at its top and closed 50 by means of a cover 3 which is held in place by bolts 4 which also serve to secure the housing and cover to the floor 1. The cover 3 has a central opening and a tubular extension 5 in line with the opening and form-

ing a casing to receive the lock mechanism. 55 A cap 6 closes the lower end of the tubular extension 5 and is centrally apertured to receive the stem 7 of a plunger 8 which is mounted in the tubular extension or casing 5. A helical spring 9 surrounding the stem 7 and confined between the plunger 8 and cap 6 normally forces the plunger 8 upwardly. A spring actuated lock bolt 10 is mounted 60 in the plunger 8 and is adapted to engage an opening 11 in a side of the casing 5 and hold the plunger depressed when the switch is open, and the circuit broken. A key operated barrel 12 is mounted in the plunger 8 and may be of any preferred construction 65 common in lock mechanism, and enables the lock bolt 10 to be actuated by means of the key 13.

The switch mechanism comprises spring blades 14 which are connected to the cover 3 by bolts or binding posts 15 to which are attached the lead wires 16. A contact 17 is attached to the lower end of the stem 7 and electrically connects the blades 14 when the plunger 8 is elevated and when said plunger is depressed the contact 17 is lowered so as to clear the blades 14, as indicated by the dotted lines in Figure 3, thereby breaking the circuit and preventing unauthorized appropriation of the vehicle.

What is claimed is:

1. A switch lock comprising a supporting member, said supporting member having an extension, a lock device rotatably and slidably mounted in said extension, a contact carried by the lock device beyond one end of the extension, contacts carried by said member outwardly of the extension and coacting with the first mentioned contact.

2. A switch lock comprising a supporting member, said supporting member having an extension, a lock device rotatably and slidably mounted in said extension, a contact carried by the lock device beyond one end of the extension, contacts carried by said member outwardly of the extension and coacting with the first mentioned contact, said locking device having a laterally movable bolt, and said extension having a keeper opening engageable by said bolt.

3. A switch lock comprising a supporting member, said supporting member having an extension, a lock device movable in said ex-

tension, a contact carried by the lock device beyond one end of the extension, contacts carried by said member outwardly of the extension and coacting with the first mentioned contact, said locking device having a laterally movable bolt, and said extension having a keeper opening engageable by said

bolt, a cap closing one end of said extension, and an expansive spring engaging said cap and said locking device to urge the first mentioned contact towards circuit closing position.

In testimony whereof I affix my signature.
LOUIE CLARK HUTCHINSON.
